MODULATING CONDITION RESPONSIVE SWITCH

George W. Crise, Columbus, Ohio, assignor to
Crise Electric Manufacturing Company, Columbus, Ohio, a corporation of Ohio

Application June 24, 1941, Serial No. 399,503

6 Claims. (Cl. 236—68)

This invention relates to improvements in condition responsive switches and more particularly condition responsive switches in which the variation from the condition to which the switch is adjusted affects not only the direction of movement of the motor controlled by the switch, but also its rate of movement.

The switch is adapted to control a motor such as shown in Figure 1 of Crise et al. Patent No. 2,134,685, November 1, 1938, or any other motor adapted to be operated in a stalled position that can be reversed by closing a two-wire circuit and stalled by inserting a suitable resistance or inductance in the circuit. The switch could be used where one motor having a greater torque is used in opposition to another or where a motor is reversed by means of gravity or a spring. The switch could also be used to operate a magnet or solenoid controlling a three-position valve or wherever a switch having an open circuit, a circuit closed through a resistance or inductance and a closed position would be useful.

An object of my invention is to provide a condition responsive switch that will regulate a control motor to remain stationary under a desired range of condition, to move slowly in a direction to reestablish the desired condition under the influence of a small variation from the desired condition and to move with increasing speed in a direction to reestablish the desired condition as the condition varies more widely from the desired range.

Other objects of the invention will be apparent from the accompanying specifications, claims, and drawing in which I describe my switch as adapted to regulate temperature, but it may be used with like effect to control humidity, pressure, light, voltage, current, mechanical movements or other variable conditions.

For a further understanding of my invention, reference is to be had to the following description and the accompanying drawing, wherein:

Fig. 1 is a front elevational view of a thermostat formed in accordance with the present invention;

Fig. 2 is a diagrammatic view of a shaded pole induction motor and associated furnace controls with which my improved thermostat may be employed;

Fig. 3 is a similar view of an electric motor utilizing a direction reversing weight.

In Figure 1 of the drawing, bimetallic element 12 carries contact 16 and is formed as shown. It is fastened to base 10 by means of post 15. Adjusting arm 11 which is made of an insulating

material is pivoted around post 15 and is frictionally held to base 10 by means of spring washer 32. Bimetallic strip 13 is fastened to a projection of arm 11 by means of rivets 22 and 23. Bimetallic strip 14 which carries the two-sided contact point 18 is fastened to bimetallic strip 13 by means of rivets 24 and 25 as is connecting lug 26. Adjusting screw 19 which carries contact point 17 operates in connecting sleeve 10 31 which is mounted in a projection of arm 11 as shown.

Resistor 27 is wound around bimetallic strip 13 from which it is electrically insulated but is so placed that heat produced in the resistor will be readily conducted to strip 13. Resistor 27 is connected to connecting lug 26 at one end and connecting screw 30 at the other. Resistor 28 is connected between connecting screws 29 and 30 as shown. Connecting lead 39 connects connecting screw 29 to connecting sleeve 31, connecting lead 37 connects connecting screw 29 to terminal bolt 33 and connecting lead 38 connects post 15 to terminal bolt 34.

Bimetallic element 12 is formed and assembled to bend in a clockwise direction under the influence of an increase in temperature. Bimetallic strip 13 is assembled to bend counter-clockwise under the influence of an increase in temperature and bimetallic strip 14 to bend clockwise. Bimetallic strips 13 and 14 are so proportioned as to counteract each other so that contact point 18 will not move in either a clockwise or counter-clockwise direction under the influence of changes in temperature affecting both alike, but will remain substantially stationary with respect to contact points 16 and 17. The temperature at which contact points 16 and 18 make contact is adjusted by moving adjusting arm 11 around post 15. As shown by the position of indicating pointer 20 on scale 21, it is shown in Figure 1 as adjusted to 70°. The further drop in temperature required to close contacts 17 and 18 is adjusted by means of adjusting screw 19.

Figure 2 shows a diagrammatic view of the motor of Figure 1 of Patent 2,134,685 connected to control the draft door of a furnace. Motor M1 has a primary coil 43 which is adapted to be energized by being connected to any suitable source of alternating current. 41—41 are fixed counterclockwise shading coils, and 42—42 are wound clockwise shading coils adapted to be connected through leads 50 and 51 to terminal screws 35 and 36 of the thermostat of Figure 1. As shown, motor M1 is connected by means of cord 55 44 to draft door 45 of furnace 46.

Figure 3 shows a diagrammatic view of a motor M2 adapted to operate clockwise by means of electrical energy when power supply leads 47 and 49 are connected to any suitable source of electric current and counterclockwise by means of weight W.

If leads 50 and 51 of the motor M1 of Figure 2 are connected to terminal bolts 33 and 34 by means of terminal screws 35 and 36 and the sum of the resistance of resistors 27 and 28 is the correct amount to stall the motor, the operation of the thermostatic switch will be substantially as follows: When the temperature drops to 70°, contacts 16 and 18 will close and the control leads of the above-mentioned motor will be connected together through resistors 27 and 28. Terminal bolt 33 connects through connecting lead 37 to connecting screw 29, connecting screw 29 through resistor 28 to connecting screw 30, connecting screw 30 through resistor 27 to connecting lug 26 and through bimetallic strip 14 to contact points 18 and 16, through bimetallic element 12 to post 15 and through connecting lead 38 to terminal post 34. The heat produced by current passing through resistor 27 will be quickly conducted to bimetallic strip 13 and will increase its temperature and cause it to bend counter-clockwise opening contacts 16-18. Bimetallic strip 13 will then drop in temperature and reclose contacts 16-18. As the temperature affecting the thermostatic switch drops farther below 70°, this closing and opening of contacts 16-18 will continue with the time the contacts are open becoming less until when the temperature reaches, say, 68° when the bending of bimetallic strip 13, due to the heating of resistor 27, has been overcome by the bending of bimetallic element 12 due to drop in surrounding temperature, contacts 16-18 will remain closed. If the temperature affecting the thermostatic switch drops still further to, say, 67° contact 18 will be forced against contact 17 by the pressure of contact 16 shorting resistors 27 and 28. Cooling of bimetallic strip 13 will at once begin and contacts 17-18 will be forced open by the clockwise pressure of bimetallic strip 13. We will then have an intermittent opening and closing of contacts 17-18 at a temperature below 67° as we had an intermittent opening and closing of contacts 16-18 above 68°. If the temperature affecting the thermostatic switch drops still farther to, say, 65° contacts 17-18 will remain in contact and the motor or other device controlled by the thermostatic switch will remain fully energized. At a temperature just below 67° contacts 17-18 will remain closed but a very small part of the time as we might have a pressure, produced by a temperature of only $\frac{1}{50}^{\circ}$ affecting bimetallic element 12, effective to close contacts 17-18 and a pressure equivalent to approximately 2° from the bending of bimetallic strip 13, to open the contacts when contacts 17-18 close and resistor 27 is de-energized. At a temperature of 66° we would have a pressure equal to 1° to close contacts 17-18 and pressure equal to 2°-1° or 1° to open them when resistor 27 is de-energized.

If power supply lead 49 of motor M2 of Figure 3 is connected to terminal bolt 34 of the thermostat of Figure 1 and lead 47 is connected to one terminal of a suitable source of electric current and terminal bolt 33 is connected to the other terminal of said source of electric current through lead 48 and if the sum of the resistance of resistors 27 and 28 is the correct amount to

stall motor M2 against the urging of weight W, the thermostat of Figure 1 would operate in the same manner when connected to motor M2 as described above when connected to motor M1.

Under the above set of conditions, the motor of Patent No. 2,134,685, or whatever device the switch was controlling, would operate the motor in a stalled position at a temperature of 67° to 68°, in one direction intermittently beginning at a very small part of the time at a temperature just below 67° to continuously at 65° and in the opposite direction intermittently beginning at a very small part of the time at a temperature just above 68° to continuously at 70°. The range of temperature when the motor would be stalled could be made any desired amount by adjusting point 17 by means of screw 18 and ranges of temperature in which movement in either direction would be intermittent can be made any desired amount by changing the sensitivity of compound bimetallic arm 13-14 and the heat supplied by resistor 27.

A condition responsive element responsive to any other condition could be substituted for bimetallic element 12 with like operation of the switch. Compensating bimetallic strip 14 could be omitted if the effect of variations in temperature in the space around bimetallic strip 13 were not objectionable. Resistors 27 and 28 could be connected in parallel instead of series with like results if proper resistances were chosen and resistor 28 could be omitted if bimetallic strip 13 were made less sensitive and resistance 27 were made the correct amount to stall the device operated, or an inductance could be substituted for resistor 28. A switch arm urged to draw away from the condition-operated contact by magnetic action could be substituted for the heater-operated bimetallic strip 13 and I contemplate such a construction as being a substantial equivalent of a heater-operated bimetallic strip.

It will be seen that a simple two-wire condition responsive switch has been provided capable of controlling a motor or other device to remain stationary under a desired range of condition and to operate in a direction to correct a variation from the desired range and to do so at a rate that increases as the condition varies farther from the desired range.

While a specific embodiment of this invention has been described, it will be understood that this is for the purpose of illustration only, and that the invention is to be limited only by the scope of the appended claims.

I claim as my invention:

1. In a control system of the character disclosed, a shaded pole induction motor having a shading coil adapted to operate the motor in one direction and a second shading coil adapted to operate the motor in the reverse direction in opposition to the first-mentioned shading coil, a heat sensitive control instrument including two sets of contacts arranged for both sets of contacts to be disengaged in one limit position, for the first set of contacts to be engaged in an intermediate position and connected to energize the said second shading coil through a resistance to a degree substantially equal to that of the first-mentioned shading coil, for both sets of contacts to be energized in the other limit position and the second set of contacts connected to energize said second shading coil to a degree predominating the first-mentioned shading coil and a heater in circuit with said sets of contacts so

connected as to be energized only when said instrument is in an intermediate position and adapted when energized to assist in opening said first set of contacts.

2. A device adapted to operate normally in one direction, a heat sensitive control instrument having two sets of contacts arranged for both sets of contacts to be disengaged in one limit position, for the first set of contacts to be engaged in an intermediate position and connected through a means to energize said device to operate it in a substantially stalled condition, for both sets of contacts to be engaged in the other limit position and the second set of contacts connected to energize said device to operate it in a direction opposite to its normal direction of operation and a heater in circuit with said sets of contacts so connected as to be energized only when said instrument is in an intermediate position and adapted when energized to assist in opening said first set of contacts.

3. A thermostat comprising a base, an indicator movably supported by said base, a normally stationary contact member carried by said indicator, a temperature deformable bimetallic element fixed at one end to said base and having its free end spaced from said stationary contact member and disposed for movement toward and away from the latter in response to variations in ambient temperature, a compounded bimetallic member composed of two linearly arranged and united sections, one of said sections deforming in response to temperature variations in a manner opposite to that of the other of said sections, one of said sections being carried by said indicator and the other of said sections being arranged between said stationary contact member and the outer end of the bimetallic element, and electrically energized heating means for supplying supplemental heat to the section of said compounded member which deforms in a manner opposite to that of the bimetallic element.

4. A thermostat comprising a base, an indicator supported by said base for pivotal movement about a fixed axis, a single temperature deformable bimetallic element fixed at one end to said base at a position in registration with the pivotal axis of said indicator, a normally stationary contact member carried by said indicator in spaced relation from the outer deflectible end of said bimetallic element, a compounded bimetallic member composed of two linearly arranged and united sections, one of said sections deflecting in response to temperature variations in a manner opposite to that of the other of said sections, one of said sections being fixed at one end to said indicator and the other of said sections being disposed between said single bimetallic element and said stationary contact member, and means for applying supplemental heat to the section of said compounded bimetallic member which deflects in a manner opposite to that of the bimetallic element when the compounded bimetallic member is in physical engagement with said single bimetallic element.

5. A thermostat comprising a base, an indicator supported by said base for pivotal movement, a normally stationary contact member carried by said indicator contiguous to its outer end, a temperature deformable bimetallic element having one end thereof secured to said base and the opposite end thereof disposed in spaced order from said stationary contact member and adapted for movement toward and away from the latter in response to temperature variations ambient thereto, a compounded bimetallic member composed of two linearly arranged and united sections, one of said sections deflecting in response to temperature variations in a manner opposed to that of the other of said sections, one of said sections being secured to said indicator and the other of said sections having its free end disposed between the outer end of said bimetallic element and said stationary contact member, electrically energized heating means for supplying supplemental heat to the section of said compounded bimetallic member which deflects in a manner opposite to that of the bimetallic element, spaced terminals carried by said base for connection with a source of electrical energy, current conducting means extending from one of said terminals to said single bimetallic element, and second current conducting means extending from said heating means and said stationary contact member to the other of said terminals.

6. A thermostat comprising a base, an indicator supported by said base for pivotal movement, a normally stationary contact member carried by said indicator, a temperature deflectable bimetallic element fixed at one end of said base and having its free end spaced from said stationary member, said element being disposed for movement toward and away from the stationary contact member in response to variations in the ambient temperature, a compounded bimetallic member composed of two linearly arranged and united sections, one of said sections deforming in response to temperature variations in an opposite manner to that of the other of said sections, means for securing one of said sections to said indicator whereby to maintain the outer end of the other of said sections in an operating position between the outer end of said bimetallic element and said stationary contact member, spaced terminals carried by said base for connection with a source of electrical energy, current conducting means extending from one of said terminals to said single bimetallic element, electrically energized heating means for supplying supplemental heat to the indicator united section of said bimetallic member which deforms in a manner opposite to that of the bimetallic element, a resistance mounted on said indicator and connected in series with said electrically energized heating means, and second current conducting means extending from the second of said terminals to said resistance and to said stationary contact member.

GEORGE W. CRISE.
